(57) **CLAIM**

The ornamental design for a disk holder with sleeve, as shown and described.

DESCRIPTION

FIG. 1 is a perspective view of the disk holder with sleeve showing our new design;

FIG. 2 is perspective view of the sleeve shown separately for ease of illustration;

FIG. 3 is a top plan view of FIG. 2;

FIG. 4 is as left side elevational view of FIG. 2;

FIG. 5 is a right side elevational view of FIG. 2;

FIG. 6 is a front elevational view of FIG. 2, the rear elevational view being a mirror image thereof;

FIG. 7 is a bottom plan view of FIG. 2;

FIG. 8 is a perspective view of the disk holder shown separately for ease of illustration;

FIG. 9 is a left side elevational view of FIG. 8, the right side being a mirror image thereof;

FIG. 10 is a top plan view of FIG. 8;

FIG. 11 is a front elevational view of FIG. 8, the rear elevational view being a mirror image thereof;

FIG. 12 is a bottom plan of FIG. 8;

FIG. 13 is a top plan view of FIG. 8 shown separately without the background for ease of illustration;

FIG. 14 is a bottom plan view of FIG. 13;

FIG. 15 is a perspective view of another embodiment of a disk holder and sleeve;

FIG. 16 is a perspective view of the disk holder of FIG. 15;
